MANUALLY REMOVABLE AND REPLACEABLE
BOTTLE CAPFrancis J. St. Jacques, Oakham Road,
North Brookfield, Mass.Filed June 12, 1962, Ser. No. 201,827
5 Claims. (Cl. 215—46)

This invention relates to a cap particularly adapted for bottles and especially of the type which includes a metal cup-like member having a cork or gasket therein and which is applied to a pouring rim or lip on the bottle by crimping the skirt or flange thereon. This type of closure is usually referred to as a crown seal.

The principal object of the present invention resides in the provision of an improvement in this type of cap which allows the cap to be removed manually from the bottle without the use of a bottle opener or any other tool; and the provision of such a cap which not only can be removed manually but can be reapplied in tight sealing condition to the container such as for instance a soda water bottle.

Other objects of the invention include the provision of a manually removable cap of the class described which is made in two pieces, a lower sealing member and a top locking member, and there being interengaging means latching the same together, these members however being quickly and easily manipulatable to remove the cap; the lower sealing member being provided with a slit or split which is held in sealing relation with respect to the bottle by the top locking member, but when the locking member is removed or in some cases merely properly manipulated without being removed, the split sealing member is easily spread apart by the fingers and removed from the bottle, and just as easily reapplied thereto and the locking member manipulated so as to bring the split parts or the sealing member into correct sealing relation.

The invention further relates to arrangements and combinations of parts which will be hereinafter described and more particularly set forth in the appended claims.

Reference is to be had to the accompanying drawings, in which

FIG. 1 is a view in elevation showing the form of the invention applied to a bottle;

FIG. 2 is a plan view, looking in the direction of arrow 2 in FIG. 1;

FIG. 3 is a sectional view along the line 3—3 in FIG. 2;

FIG. 4 is a plan view of the sealing member showing the same open and detached from the bottle;

FIG. 5 is a bottom plan view of the locking member;

FIG. 6 is an exploded view in side elevation illustrating a modification;

FIG. 7 is a plan view of a modification of the lower member;

FIG. 8 is a plan view of the locking member to be applied to FIG. 7, and

FIG. 9 is a side view thereof, part in section.

In carrying out the present invention, the same is illustrated as a crown seal applicable to a soda water bottle or the like. The construction embodies two members, one of which is an upper locking member generally indicated at 10 and the other of which is the lower seal member generally indicated at 12. As shown in FIGS. 2 and 4, the lower member 12 is in general very similar to the well known conventional crown seal having a fluted skirt 14 which is crimped to secure it to the pouring lip 16 of the container 18 of well known type, but in this case the top flat cover portion thereof is pierced or apertured to form an elongated opening as at 20.

2

Also member 12 is split or slit along an arcuate line 22 forming an arcuate member 24 separated at one area as at 26 but at the opposite end of arcuate member 24 it is still attached to the main body of the cap in the area at 28 by a part of the skirt 14. It will be seen that member 24 is quickly and easily separated from the main portion of the member 12 manually because the metal at 28 is very small and weak but provides that member 12 is all in one part.

The locking member 10 is a plain cup-like member which has a continuous edge flange 30 and at its inner aspect thereof is provided with a fastening device such as at 32. This fastening device is a small sheet of material, providing a pair of tabs shown in FIG. 5, these being slightly spaced from the inner surface of the locking cap member 10 and as a matter of fact may be provided with slightly upturned lip portions 34 if desired. This member may be welded or otherwise secured at 36 to the interior part of the cap.

This cap is usable in any existing capping machinery and as provided, the parts are locked together as shown in FIG. 3 and the bottle is capped in exactly the usual manner, it being noted that the flange 30 of the locking cap 10 holds the arcuate member 24 in tight gripping relationship with respect to the main body portion of the lower cap member 12, but when it is desired to open the bottle it is merely necessary to apply the fingers to the top locking member 10 and turn it 90° so that the tabs 32 coincide with the aperture 20 when the top locking cap may be lifted off, in which case the arcuate member 24 is then free to be manually moved to the FIG. 4 position, completely opening the bottle.

The reverse of this operation is quickly and easily made also in order to recap the bottle simply by placing the lower member 12 on the pouring lip and applying the flange 30 to the part 24 for drawing it into sealing engagement with respect to the pouring lip of the bottle and then giving the 90° turn to reposition the parts in locking condition as shown in FIG. 3.

As a variation of this device, as shown in FIG. 6, the lower sealing member 40 is the same as before described including the slit at 22, 26, etc. but in this case it is provided with a cam-shaped or interrupted screw thread parts 42 which are engaged by inturned lugs 44 indicated in dotted lines in FIG. 6 on the top locking member 46. The operation is substantially the same as before. The two parts 40 and 46 are provided in locked condition with the tabs 44 lying under the projections 42, but when it is desired to remove the cap the locking cap 46 is twisted so as to free it and turn tabs 44 from the lugs 42 and then the operation is the same as above described, it being noted that the cap 40 has a slit 48 which compares to that at 26 in FIGS. 1 and 2 for instance.

A third form of the invention is a single unit and is shown in FIGS. 7, 8 and 9 wherein the sealing member is generally indicated at 50. This sealing member has a slot 52 as before forming the two sealing members (53 and 55) also as before but in this case there is merely a circular member 54 centrally of the sealing member and this provides for a rotary center or hub such as a headed rivet 56 mounted on a locking member generally indicated at 58 so that the latter is rotatable on the sealing member 50 but not removable. The locking member 58 is composed of a relatively large portion 60 having a skirt as at 62 and a narrower radial portion 64 having a skirt as at 66. It will be seen that the narrow portion 64 being made of the usual thin material of which crown seals are made can be bent up to the dotted line position or higher in FIG. 9 and in this position it is useful as a handle to swivel or rotate locking member 58 relative to sealing member 50 to leave the slit 52 in an unlocked con-

dition so that the portion 53 thereof can be moved away from the portion 55 to remove the entire cap without removing the locking member from the sealing member. Also, this cap is easily replaced and resealed by the reverse procedure, providing skirt parts 62 and 66 to grip the opposite portions of the crimped parts at 53 and 55.

It will be seen that this invention provides a relatively simple device which solves the problem of opening bottles using crown seals without the use of any tools, bottles, etc.

Having thus described my invention and the advantages thereof, I do not wish to be limited to the details herein disclosed, otherwise than as set forth in the claims, but what I claim is:

1. A closure cap comprising a sealing member adapted to be applied to the mouth of a container, said sealing member including a cover portion and a crimping depending skirt, said skirt having a slit therein, said slit extending substantially across the cover portion and dividing the sealing member into a plurality of permanently connected but manually interpivoted cooperative partial sealing members, each partial sealing member including a portion of the skirt, a separable locking cap, a peripheral skirt, on the locking cap to engage all the partial sealing members exteriorly thereof, pressing generally radially inwardly thereon to hold the same in sealing relation to the mouth of the container, and interengaging means between the sealing member and the locking cap holding the peripheral skirt of the locking cap to the skirts of the partial sealing members in locked condition of the said partial sealing members, said locking cap being manually removable bodily to release the skirts of the partial sealing members, whereby the latter may be manually pivoted away from each other to free the sealing member from the container mouth.

2. The closure cap of claim 1 wherein the interengaging means includes a tongue and a cooperating slot therefor.

3. The closure cap of claim 1 wherein the interengaging means includes a tongue and a cooperating slot therefor, the locking cap being rotatable relative to the sealing member to secure and release the members by the tongue and slot.

10 4. The closure cap of claim 1 wherein the interengaging means includes cooperating peripheral members on the locking cap and sealing member, the cap being relatively rotatable to lock and free the sealing member.

15 5. A closure cap for a container having a mouth comprising a sealing member including a crimpable skirt, the sealing member being at least partially divided providing

20 a plurality of relatively movable skirt portions a separable locking cap including a peripheral skirt to engage the relatively movable skirt portions of the sealing member and hold the same in sealing relation to the mouth of the container, rotatably actuated means securing the locking cap to the sealing member in skirt portion holding condition of the sealing member, said locking cap being manually rotatable to release the securing means so that the cap is wholly released from the sealing member, providing for manual motion of the sealing member skirt portions to remove the sealing member from the mouth of the container.
